UNITED STATES PATENT OFFICE.

ANTON DAMERIS, OF COLOGNE, GERMANY, ASSIGNOR TO CORNEL ESSER, OF COLOGNE, GERMANY.

DEVICE FOR PREVENTING RAILS SHIFTING OR CREEPING.

No. 892,505.

Specification of Letters Patent.

Patented July 7, 1908.

Application filed December 18, 1907. Serial No. 407,016.

To all whom it may concern:

Be it known that I, ANTON DAMERIS, subject of the German Emperor, residing at Cologne, Germany, have invented new and useful Improvements in Devices for Preventing Rails Shifting or Creeping, of which the following is a specification.

The present invention has for its object a device for preventing rails shifting or creeping.

For preventing railway rails shifting or creeping, so-called wedge-lock clamps have hitherto been used which clasp the foot of the rail with a bow and which are held to the rail by wedges which abut against the sleepers.

In accordance with the present invention two clamps which are like one another and placed each with two hooks round the foot of the rail are employed, the one of which 20 clamps abutting against the sleeper lying in the direction in which the rail shifts. Both clamps lie against one another with sloping faces in such a manner that the clamping action is increased with certainty by the shifting movement. Also the action of this device is particularly powerful because the foot of the rail is clasped by four hooks in all.

In order that the invention may be clearly understood, reference is made to the accompanying drawing in which one embodiment is represented by way of example and in which—:

Figure 1 is a side elevation showing the device and the manner in which it is employed; Fig. 2 is a plan of a rail with clamps thereon; Fig. 3 is also a plan showing the clamps in the position before they are attached to or moved entirely away from the rail, whereas Fig. 4 is a vertical section in the plane A—B in 40 Fig. 2.

The new device consists of two like plate-shaped bodies or clamps a, a' which at the one end at b, b' are bent downwards nose-shaped and at the other end at c, c' are sloped away laterally. On their long sides these plates have at both sides an upwardly bent hook d, e and d', e' . These hooks are preferably displaced relatively to one another in the longitudinal direction and, of course, are at a distance from one another in the transverse di-

rection about equal to the breadth of the foot f of the rail.

In order to arrange the clamping device on the foot of the rail, one of the clamping plates a is first placed against the foot f of the rail 55 from below slantwise of the latter (Fig. 3), is then turned so far horizontally that the hooks d and e clasp the foot of the rail, and lastly is pushed so far towards the sleeper situated in the direction in which the rail shifts 60 until the nose b of the clamp hits against it; the direction in which the rail shifts or creeps is indicated by arrows in Figs. 1-3. The other clamping plate a' , is then brought on to the foot of the rail in similar manner in the 65 opposite position, rotated and pushed against the first plate, so that the sloped ends c, c' of both plates abut against each other. The two plates are then pressed firmly against each other by means of a few blows of the 70 hammer directed against the second clamping plate a' , whereby the hooks d, e and d', e' are clamped immovable on the foot of the rail, the plates acting as levers when the sloped ends c, c' slide one on the other. It is 75 clear that the clamping action, that is to say the frictional resistance between the hooks and the foot of the rail, is at once increased when the rail commences to creep and that this movement at once ceases in this manner. 80

What I claim as my invention and desire to secure by Letters Patent is:—

The combination with a rail and a sleeper supporting the same, of a pair of like clamps provided with a hook at each side adapted to 85 clasp the foot of the rail and having one end sloped off laterally and the other end bent downwards, whereby said clamps are attached to the foot of the rail oppositely, contacting one another with their sloped ends 90 and the bent end of one clamp abutting against the sleeper.

In testimony whereof I have signed my name to this specification in the presence of two subscribing witnesses.

ANTON DAMERIS.
